GAME TABLE

Roy B. Johnson, 1615 Willow St.,
Alameda, Calif. 94501

Filed Aug. 28, 1969, Ser. No. 18,905

Term of patent 14 years

Int. Cl. D21—01

U.S. Cl. 34—5

FIG. 4

FIG. 1 is a perspective view of a game table showing my new design;

FIG. 2 is a side elevational view thereof;

FIG. 3 is a top plan view thereof; and

FIG. 4 is an end elevational view thereof.

I claim:

The ornamental design for a game table, substantially as shown.
